UNITED STATES PATENT OFFICE

JOHN ARTHUR, OF ZANESVILLE, OHIO

TWINE CUTTER

Application filed March 19, 1929. Serial No. 348,257.

This invention relates to cord or twine cutters such as are used in stores for severing the cord on tied packages and the like.

A primary object of the invention is to provide a device of this character which may be located so as to occupy a minimum amount of space and yet be accessible for use.

Another object of the invention is to provide a twine cutter so constructed as to be easily and quickly installed and when installed will effect a maximum saving of time in the cutting operation and in which the cutter blade is mounted so as to be protected against injury and against injuring those using it.

Another object is to so construct a device of this character that the parts may be readily separated for repairing or furnishing a new blade when such becomes necessary.

In carrying out these objects, the invention is susceptible of a wide range of modification without departing from the spirit or sacrificing any of the advantages of the claimed invention; there being shown in the drawings for illustrative purposes a preferred and practical form, in which:

Figure 1 represents a perspective view of a portion of a counter showing this improved cutter in operative position;

Fig. 2 is a detail perspective of one member of the cutter, with the blade shown in dotted line;

Fig. 3 is a similar view of the other member of the cutter;

Fig. 4 is a transverse section taken on the line 4—4 of Fig. 1, and

Fig. 5 is a similar view taken on the line 5—5 of Fig. 1.

In the embodiment illustrated the cutter 10 constituting this invention is shown mounted on one end of a table or counter 1 which has a pin or rod 2 extending upwardly therefrom preferably near the corner to receive and rotatably support a ball 3 of twine such as is ordinarily used in stores for tying up packages.

The cutter 10 is composed of two members 11 and 15 slidably and separably connected and between which is designed to be mounted the cutting blade 20. This blade 20 as shown

is in the form of a safety razor blade having cutting edges along both top and bottom so as to be reversible when desired and equipped with apertures 21 to receive out struck tongues 12 formed on the body of the member 11 and which face in opposite directions as shown clearly in Fig. 2 so that when the blade is mounted thereon it will be held against sliding movement.

The member 11 is designed to be attached to the counter or other support by means of screws 22 passed through apertures 13 in the body of the member 11. Inturned flanges 14 are formed along the side edges of the member 11 which is preferably struck out of sheet metal and these flanges form guides to slidably receive the member 15. A longitudinally extending slot-like opening 23 is formed on one edge of the member 11 and has a mouth 24 opening through said edge and forms in connection with a similar opening 26 in the member 15 provided with a mouth 27 a chamber to receive the cord 4 to be severed.

The plate or member 15 is made wider at its front end than at the rear of the opening 23 and the outlet or mouth 24 of said opening is located at the junction of the wider portion of this plate with the narrow portion of the plate as is shown clearly in Figs. 1 and 2.

Member 15 is struck out of a sheet of metal with the body portion thereof outwardly bulged for the greater portion of its length as shown at 16, said bulged portion gradually merging at its inner end into the body of the plate. This bulged portion operates to space the members apart during their sliding engagement, the edges of said plate 15 being adapted to extend under and be guided by the inturned flanges 14 of the member 11. The wider portion of the plate 15 is designed to slide in the flanged edge 25 of the wider portion of the plate 11.

The upper edge of the wider portion of plate 15 is also provided with an open slot 26 provided with a mouth 27 which registers when the plates are in extreme retracted position, with the slot 23 of plate 11 as is shown clearly in Fig. 1. This slot 26 as above de-

scribed has a mouth 27 at its inner end which registers with mouth 24 of plate 11 and is designed to receive the cord to be cut by the blade 20 which is clamped between the members 11 and 15 with its cutting edge projecting into the registering openings or slots 23 and 26 forming the lower wall thereof. At the wider outer end of the member 15 is formed a finger grip 17 provided by rolling inward one end of plate 15. This hand grip 17 is designed for the manipulating of this plate relatively to plate 11. The bulged portion of the plate 15 also forms a chamber to receive the heads of the fastening screws 22 as is shown in Fig. 5 and permits said plate to slide freely without contacting or binding against said screw heads.

In the use of this cutter the parts being assembled as shown in Fig. 1 and a ball of cord placed on the pin 2 with the free end 4 of said core loose it will be understood that this cord end may be used to pass around a bundle and tied; then by simply inserting the portion beyond the tied bundle in the opening in the upper edges of the plates entered through the registering mouths 24 and 27 the cord may be moved downwardly against the sharp edge of the cutting blade 20 and quickly severed.

When it is desired to reverse the cutting edge of blade 20 all that is necessary is to draw outward the plate or member 15, disengage the blade from the tongues 12, reverse it and again reengage it and then replace the member 15 which will clampingly hold said blade in operative position again ready for use.

The extreme simplicity of this device and the fact that old safety razor blades may be used to form the severing element 20 renders the upkeep of the device practically nil. Moreover with the blade housed between the two members 11 and 15 and having the cutting edge thereof extended upwardly from the lower walls of the registering openings said blade is protected against being injured itself and also against contact with persons using it.

Without further description it is thought that the features and advantages of the invention will be readily apparent to those skilled in the art, and it will, of course, be understood that changes in the form, proportion and minor details of construction may be resorted to, without departing from the spirit of the invention or its scope as claimed.

I claim:

1. A cord cutter comprising a pair of clamping plates arranged one on the other in sliding relation and having means to hold them against separation, said plates each having a recess opening through one side edge and extending longitudinally of the plate, said recesses being adapted to register when the plates are brought to a predeter-

mined position, a cutting blade clamped between said plates with its cutting edge extending into said recesses, one of said plates having a transversely arranged tubular member to form a hand grip.

2. A cord cutter comprising a pair of clamping plates adapted to be arranged one on the other and to slide longitudinally in relation to each other, one of said plates having inturned flanges along its side edges to form guiding means for the other, both of said plates having one end made wider than the other and said wide ends provided near one edge with longitudinally extending open slots, the openings in said slots being arranged at the junction of the wide portions with the narrower portions of the plates, and a blade to be clamped between said plates with one edge projecting into said slots.

3. A cord cutter comprising a pair of clamping plates adapted to be arranged one on the other and to slide longitudinally in relation to each other, one of said plates having inturned flanges along its side edges to form guiding means for the other, both of said plates having one end made wider than the other and the said wide ends provided near their upper edges with longitudinally extending open slots, the openings in said slots being arranged at the junction of the wide portions with the narrower portions of the plates, said open slots being adapted to register when the plates are in operative position, a blade to be clamped between said plates with one cutting edge projecting into said slots and means for securing one of said plates to a support.

4. A cord cutter comprising a pair of clamping plates adapted to be arranged one on the other and to slide longitudinally in relation to each other, one of said plates having inturned flanges to form guiding means for the other, both of said plates having one end made wider than the other and said wide ends provided near their upper edges with longitudinally extending slots open at one end, the openings in said slots being arranged at the junction of the wide portions with the narrower portions of the plates, said open slots being adapted to register when the plates are in operative position and to form a blade seat, means for securing one of said plates to a support, and an outwardly bulged portion in one plate to adapt it to move freely over the securing means of the other plate without contacting them.

Signed at Zanesville, in the county of Muskingum and State of Ohio, this 14th day of March, 1929.

JOHN ARTHUR. 125
